HEATING AND AIR CONDITIONING UNIT

Donald Hess Powers, Tacoma, Wash.

Application March 5, 1937, Serial No. 129,251

1 Claim. (Cl. 126—110)

My present invention relates to the art of constructing heating and air conditioning equipment and more particularly to a heating and air conditioning unit.

In my present equipment full use has been made of modern methods of fabricating steel plate to the end that I have provided a unit that is complete within itself, which permits of the most economical operation, yet by virtue of its arrangement and construction, can be made at a very low price. It consists of, preferably, a welded steel furnace, air tight burner, humidifier, filters, draft control, blower, plenum chambers, and duct system, the combination of which gives very high efficiency and economy. My system differs from like equipment inasmuch as the furnace itself consists of a large, vertical combustion chamber surrounded by a circular inner casing forming the primary warm air plenum chamber constructed in such a way as to induce impingement, upon the combustion chamber, of air entering the plenum chamber through the blower so that all the air is forced into direct contact with all the heated surfaces of the combustion chamber.

I next provide a secondary combustion chamber or gas consumer, consisting of a cylindrical chamber made of welded steel with a coaxially disposed cylindrical chamber made of welded steel 30 with a coaxially disposed cylindrical tube passing directly through the same to which, in turn, inwardly directed, vertical steel fins are welded. This secondary combustion chamber is placed directly above the blower and surrounded with 35 an inner casing spaced around the secondary combustion chamber so that all air being drawn through it by the blower will impinge directly against the surfaces which are heated by the flue gases as they pass through the secondary 40 heating chamber to the chimney. This combination forms a secondary warm air plenum chamber. The blower draws return air from the house through and around the secondary combustion chamber then forces the air through the primary 45 plenum chamber to the heating air ducts. This arrangement differs from other furnaces observed as the secondary combustion chamber is placed directly in the cold air return to blower thereby forming a secondary warm air plenum 50 chamber. The cold air plenum chamber consists of automatic louvers or dampers placed in such a manner that the heat from secondary combustion chamber cannot heat the cold air entering cold air plenum chamber because the 55 dampers will be so balanced as to close, when

the blower shuts off, and to open by suction of the blower when the blower starts. The filters may be of conventional dry filter type located between the damper and return air ducts. An automatic humidifier is inserted in the primary 5 warm air plenum. The blower is so arranged that it operates automatically on temperature changes of the furnace.

A feature of this heating plant is the use of a fuel burner having an automatic air control 10 so as to shut off all air movement through the normal draft passage, and a barometric draft control which automatically closes a tight damper in the smoke pipe when the burner shuts off, thereby sealing the heated air in the combustion 15 chambers until all heat has been extracted by the blower, thus assuring high efficiency and low cost of operation.

The principal object of my present invention is to provide a unitary structure for winter air 20 conditioning that is so arranged and constructed that it provides a very efficient heating unit.

An important object of my invention is to provide a unit of the character described which because of its construction can be produced at a 25 very low cost and consequently can be available to many of the smaller home owners.

Another object of my invention is to provide a unit which can for the most part be almost entirely fabricated from metal plate without 30 the use of expensive castings which are always subject to breakage under conditions of repeated heating and cooling.

Another important object is the provision of a complete heating unit that is so securely welded, or riveted, together from sheet material that 35 there can be no intermingling of the product of combustion with the air being heated.

Another object of my invention is to provide a unit that will automatically be sealed as soon as 40 the fuel burner stops functioning, to the end that no heat will be lost up through the smoke stack, but will be all converted into effective heating for the air being circulated.

Another important object is the provision of 45 dead air space surrounding the combustion chambers and plenum chambers so that the generated heat is not dissipated through the outer shell.

Other and more specific objects will be apparent from the following description taken in connection with the accompanying drawings, wherein

Figure 1 is an elevation, in section, taken longitudinally through my unit. 55

Figure 2 is a fragmentary view in perspective of a portion of the combustion fan of a fuel burner forming an essential part of my equipment.

5 Figure 3 is a cross-sectional view, in plan, taken along the line 3—3 of Figure 1.

Figure 4 is a perspective view, with the top removed, to better illustrate the arrangement of parts within my unit.

10 Referring to the drawings, throughout which like reference characters indicate like parts, 6 designates the fire box of my furnace proper. This I normally form of reasonably heavy sheet metal, it being customary to use metal three-15 sixteenths to one-quarter of an inch in thickness for the ordinary residence unit. This is provided with the usual fire door 8 and is lined in its lower portion as by the refractory material at 10. This lining is normally fire brick, or similar material, so that if necessary it can be replaced. For convenience and strength the fire box proper is normally formed in a circular shape. Coaxially disposed with the fire box 6 is the main or primary heating chamber 12. This is 20 formed by a cylindrical structure of, preferably, welded steel plate, spaced reasonably close to the furnace proper so that air passing through chamber 12 must, of necessity, impinge upon the heated fire box 6. Chamber 12 communicates directly 25 with the heating air ducts 14 leading to the heating registers in the various rooms of the building, or home, following the principles of normal piped air heating. Where humidifying is desired, it is installed directly above the fire box, at the top of chamber 12, as is indicated at 30 16 wherein a shallow pan is employed which is fed from a pressure water pipe 18 which in turn is controlled by the float valve 20.

The outlet through which the heated gases of 40 combustion from chamber 6 pass, is pipe 22. This carries the gases into a secondary combustion chamber 24 which is formed as an annular passageway and has an outlet in pipe 26 which carries the gases to the chimney. Attention is invited particularly to Figure 1, wherein the general relationship in size and placement between the secondary chamber 24 and the fire box 6 proper is generally shown in a preferred arrangement. Pipe 22 is taken off near the top of chamber 50 6 and enters well up in chamber 24. The hot gases circulate around chamber 24, then descend to go out pipe 26. This is not, however, a very tortuous path for these gases and as a result the draft obtained in the unit is exceptionally good. To further assist in the heat transfer from chamber 24 to the incoming air, I have provided within a central pipe 28, a plurality of inwardly extending fins as 30. These are preferably welded to pipe 28 so that intimate contact is obtained to the end that maximum transfer of heat may be accomplished. The number of these fins will be determined by the size of the unit, it being desirable at all times to pass the air through relatively narrow passageways, 60 with frequent changes in the direction of movement of the air, to insure that at some point in its travel it will come in intimate contact with the heat transferring surfaces.

The entire secondary combustion chamber is 70 coaxially disposed within the plenum chamber 32 providing an annular passageway 34 entirely around this secondary combustion chamber so that the incoming cold air from the cold air registers, or outside source, passes either through, 75 or around, this unit due to the suction created

by blower 36. This blower is of the large capacity, low pressure type driven by any suitable source of power as electric motor 38. It creates a movement of air which draws air in through the cold air pipe 39 and passes it out around the firebox through chamber 12 and out through pipes 14. As a matter of convenience in servicing and for other inspection purposes, I provide the inspection door or plate 40 which provides access to the blower and blower motor. 10

A preferred type of oil burner of an automatic nature is shown at 42. This burner should be of a type that will close its air intake passageway as soon as the burner itself shuts off. One convenient means of accomplishing this end is 15 shown in Figure 2 wherein the blades 44 of the combustion fan assembly 46 are mounted on pivots as 47 and as soon as the power of the motor is shut off, coil springs 48 close these vanes, one on the other, so as to seal the air passageway. 20 This, together with the automatic or balance type of damper, at 50 in the chimney pipe, insures the retaining of the heat within either the furnace firebox 6, itself, or within the secondary combustion chamber 24 so that there will 25 be no inrush of cold air to cool off the furnace and no opportunity for the heated air to be drawn up the chimney. As a result the blower, continuing to circulate the air through the system, can take full advantage of all of the heat 30 stored within the unit. It will be understood, it is believed, that any type of mechanical burner as for coal, or comminuted fuels, may be so arranged and used with my unit.

It is to further the economy in heating due 35 to the sealing of the furnace and the secondary combustion chamber that I have provided the dead air plenum chambers 52 and 54, and a dead air chamber 55 between said chambers. These serve to insulate the heated surfaces 40 against undue radiation and make it possible to economically operate the unit on the basis of intermittent service where the heat is built up within the unit, then, the oil burner shuts off, and the blower, circulating the air through the 45 system, draws out all of the heat that might otherwise be dissipated and lost. When the blower is shut off damper 57 in pipe 39 closes automatically and prevents convectional circulation. Air filtering is accomplished by installing a 50 desired number of filter units 58, preferably in the cold air return pipe as illustrated in Figure 1.

The foregoing description and the accompanying drawings are believed to clearly disclose a preferred embodiment of my invention but it 55 will be understood that this disclosure is merely illustrative and that such changes in the invention may be made as are fairly within the scope and spirit of the following claim:

Having thus fully described my invention, what 60 I claim as new and desire to secure by Letters Patent is:

An air conditioning unit for use with a furnace and its smoke pipe, said unit comprising a casing, an interior drum supported in the casing and 65 a closed annular insulating jacket between said drum and casing, said casing also having a wall spaced from the adjoining furnace wall to form part of an insulating jacket for the furnace, said drum and its jacket forming an upper intake 70 cold-air chamber, said drum and jacket also forming a heated outlet chamber in the bottom portion of the casing, said smoke pipe passing through said annular jacket and connected directly to the interior of the drum above its ver- 75

tical center, an outlet smoke pipe connected to the interior of the drum at its lower end and passing through the drum-jacket, said drum being spaced within its jacket to form an annular air passage open to said chambers, a central air pipe extending through the drum and open to the chambers, a number of upright fins forming air channels within the pipe, a fan and a motor therefor in the bottom portion of the outlet chamber, and said fan having a discharge duct passing through the jacket of the furnace and opening to a hot air chamber of the furnace. 5 8

DONALD HESS POWERS.
